(57) **CLAIM**

We claim, the ornamental design for a face shield for safety helmet, as shown and described.

DESCRIPTION

FIG. 1 is a top and front perspective view of a face shield for safety helmet, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a right side elevational view thereof, the face shield for safety helmet applied to a helmet; and,

FIG. 9 is a right side elevational view thereof, the face shield for safety helmet applied to a helmet in an alternate position.

The helmet in FIGS. 8 and 9 is shown in broken lines for illustrative purposes only and forms no part of the claimed design.
